UNITED STATES PATENT OFFICE.

DONALD M. BLISS, OF CHICAGO, ILLINOIS, ASSIGNOR TO BODINE ELECTRIC COMPANY, OF CHICAGO, ILLINOIS, A CORPORATION OF ILLINOIS.

SHORT-CIRCUITING DEVICE.

Application filed July 25, 1927. Serial No. 208,217.

My invention relates to short-circuiting devices for repulsion induction motors of the single-phase commutator type, as employed for automatically short-circuiting the entire 5 commutator when the motor has attained a predetermined speed, and particularly to the class of such short-circuiting devices in which the short-circuiting member is moved in one direction by the action of centrifugal force 10 on weights and in the opposite direction by a retracting spring.

Among the general objects of my invention are those of providing a device for this purpose consisting of very few and easily 15 manufactured parts, and one which will be easy to assemble or disassemble. Further objects are those of providing a movable short-circuiting member arranged for engaging peripheral and tapering parts of the commutator 20 segments with a wiping action and with freedom for movement both rotationally and longitudinally of the commutator, and of providing a short-circuiting device in which the device-contacting portions of the commutator are exposed for convenient cleaning and 25 refinishing when the motor is not running. My invention also provides a construction in which a single-piece member is directly engaged both by the centrifugally movable 30 weights and by the retracting spring, and in which this member also contacts with the commutator segments to effect the short-circuiting.

Moreover, my invention provides a short-circuiting device in which the major operating 35 parts are all freely rotatable on the shaft of the motor, whereby the short-circuiting member continually presents different portions to any given commutator segment, and 40 whereby I reduce internal friction in the device.

Still further and also more detailed objects 45 will appear from the following specification and from the accompanying drawings, in which

Fig. 1 is a side elevation of one end of the commutator of an armature, together with a central and axial section through a short-circuiting device embodying my invention, 50 showing the latter as it appears when the motor is standing still.

Fig. 2 is a section similar to the right-hand upper corner portion of Fig. 1, showing the disposition of the parts when the motor has

speeded up so that the short-circuiting member engages all of the commutator segments. 55

Fig. 3 is a view taken from the line 3—3 of Fig. 1, with portions of the cap and of the short-circuiting member broken away.

Fig. 4 is a perspective view of the lower 60 weight of Fig. 3 together with guide stems carried by this weight.

In the illustrated embodiment, the commutator segments 1 are all beveled at their right-hand end to a uniform frustro-conical 65 form to afford sloping contact portions 2. Sleeved upon the shaft 3 adjacent to this end of the armature is a bushing 4. This bushing has a radially enlarged end 5 at its outer end, and the bushing is held close to the armature by any suitable means, such as a pin 5^a driven through the bushing end 5 into the shaft. 70

The main shank portion 4 of the bushing extends freely through central perforations 75 in the back 7 of an outer weight-guiding member, and in the flat and disk-shaped main portion 8 of a short-circuiting member, and these portions 7 and 8 are spaced longitudinally of the shaft by a pair of relatively slidable 80 weights 9. The short-circuiting member also includes an annular cam portion 8^a which flares radially outward toward the back of the said cap, a relatively stiff tubular portion 8^b extending toward the commutator from the 85 outer edge of the cam portion 8^a, and a contact portion 8^c which flares toward the commutator at an angle corresponding to the slope of the segment contact portions 2.

The weights 9, which desirably are of a non-magnetic metal (such as brass or a die-cast metal) are slidably connected to permit their moving radially of the shaft both toward and 90 away from each other while preventing relative movement of the weights circumferentially of the shaft, thus keeping the weights diametrically opposite each other. For this purpose I am here showing the weights as 95 connected by a pair of parallel rods 10, each of which rods is secured to the lower weight 100 9 (in Fig. 3) and slides freely in a bore 11 in the upper weight.

Each weight has its radially outward edge 9^a beveled towards the commutator to a shape conforming substantially to the flare of the cam portion 8^a of the short-circuiting member. Consequently, a movement of the weights radially outward of the shaft will 105

cause the said portions 9^a by a cam action on the cam portion 8^a of the short-circuiting member to move the latter member towards the commutator. Such motion is resisted by 5 a compression spring 12 interposed between the armature and the disk-like main portion of the short-circuiting member, and by suitably proportioning the strength of the spring to the weights, I can deter the above described 10 cam action until the armature reaches a substantially predetermined speed. Likewise, by suitably proportioning the sizes of the various elements, I can cause the longitudinal sliding movement of the short-circuiting 15 member (as due to the said cam action when the weights fly outward) to force the flaring contact portion 8^c of that member into firm contacting engagement with the tapering end portions 2 of the commutator segments. To 20 secure an effective contacting with all of these segments, I preferably provide this portion 8^c with radial slits 13, as shown in Fig. 3, which slits divide the said portion into contact fingers as shown in Fig. 3.

25 When the current to the motor is shut off, so that the speed of the armature falls, the radially outward centrifugal thrust on the weights drops, so that this thrust can no longer overcome the pressure of the spring 12. 30 This spring pressure 12 then forces the short-circuiting member away from the armature, and the cam portion 8^a of the latter forces the weights radially inward until stopped by engagement with the shank 4 of the bushing, as 35 shown in Fig. 3. Since the spring, the short-circuiting member, the interconnected weights and the cap are all freely rotatable on the bushing (and hence with respect to the shaft), these parts can readily shift rotationally with respect to the commutator. 40 Consequently, the contact fingers on the short-circuiting member—which member desirably is made of a spring bronze or the like—not only engage the beveled segment 45 ends with a wiping movement longitudinally of the commutator, but also in continuously changing positions of the contact fingers with respect to the numerous commutator segments. This rotational shifting may be augmented by a shifting in the position of the 50 weights rotationally of the two members between which the weights are interposed. Consequently, the provisions for the free rotation of so many parts of my device cause the wear to be distributed, thus prolonging the life of my contrivance.

55 Moreover, when the armature is standing still—as in Fig. 1—the beveled commutator ends are readily accessible both for examining them and for sand-papering or otherwise refinishing them if desired, and the contact finger portions of the short-circuiting member are likewise readily accessible. This makes it easy for the user to maintain the 60 motor in fine working condition, which has

not been possible with devices in which the contact is on undercut segment parts or on the flat ends of segments.

While a flat disk portion 7 suffices as the outer guide for the weights, I desirably provide this outer weight-guiding member with a peripheral flange 7^a extending toward the fingered contact portion 8^c, thereby housing the major portion of my device against the entrance of dust. If any dust or the like should still enter, this will readily be thrown out by centrifugal force, so that my device is practically self-cleaning.

Being void of all levers, pivot pins and the like, my entire device is unusually simple and 80 obviously inexpensive, besides being unusually easy to assemble. Moreover, it requires no special commutator construction, as the mere beveling of the free end of an ordinary commutator suffices. So also, my entire device is highly compact longitudinally of the armature.

Both of the two cup-shaped members between which the weights are disposed are 85 easily formed by punch-press operations, and when the armature is standing still, the spring 90 clamps the weights between them. This clamping action continues to prevent a radially outward movement of the weights until the speed is such that the centrifugally actuated thrust of the weights, acting through the 95 said co-operating cam portions, overcomes the pressure of the spring. Consequently, I can easily make my device responsive to any selected speed by merely choosing a 100 spring of suitable power in proportion to the weights.

By interposing a cylindrically bored tubular portion 8^b between the contact fingers and the annular cam portion of the short-circuiting member, I make this connection rigid for 105 readily transmitting the thrust, and by extending the beveled cam portions of the weights over large arcs I distribute the cam 110 thrust over a considerable portion of the circumference of the substantially cup-shaped short-circuiting member. However, while I have pictured and described my invention in an embodiment including two weights, a bushing end for receiving the thrust, and a 115 tubular housing portion on the outer weight-guiding member, I do not wish to be limited to these or other details of the construction and arrangement thus disclosed. Many 120 changes might obviously be made without departing either from the spirit of my invention or from the appended claims.

I claim as my invention:

1. The combination with a commutator, of a single-piece and substantially cup-shaped short-circuiting member movable axially of the commutator and having the radially outer portion of its cup bottom tapered radially inward toward the commutator to form an annular cam portion, weights movable radially 125 130

of the commutator and having radially outer beveled portions continuously engaging the said annular cam portion, and guide means for preventing movement of the weights longitudinally away from the commutator, the guide means and the short-circuiting member being freely and independently rotatable with respect to the commutator about the axis of the latter, the said member having its mouth end portion adapted to engage the commutator.

2. The combination with a motor having a shaft projecting beyond its commutator, of centrifugally actuated short-circuiting means comprising: two weights at opposite sides of the projecting shaft, a pair of guides at opposite sides of the weights and both freely and independently rotatable with respect to the commutator, stop means fast upon the shaft for maintaining the guide furthest from the commutator at a fixed distance from the commutator, the other guide being movable toward and away from the commutator and having integral contact fingers adapted to short-circuit the commutator, the said other guide and the weights having interengaging frustro-conical cam faces for causing radially outward movement of the weights to move the last named guide toward the commutator; the said short circuiting means being bodily detachable as a unit from the motor.

3. A commutator and short-circuiting device combination as per claim 2, in which the stop means include rods respectively fast on one and slidably engaged by other of the weights.

4. The combination with the commutator of an induction motor, of a short-circuiting member slideable towards and away from the outer end of the commutator, spring means resisting the movement of the said member toward the commutator, and weights movable radially outward of the axis of the commutator by centrifugal force; the weights and the said member having interengaging frustro-conical cam faces disposed so that when the weights are moved radially outward by centrifugal force the said interengaging cam faces will cause the short-circuiting member to move axially toward and into engagement with the commutator, and will also cause a movement of the said member away from the commutator to move the weights radially inward in combination with a cup-shaped guide member having a flat and rigid cup bottom

engaging the side of the weights away from the commutator, the said guide member housing the major portion of the short-circuiting member, and means for preventing movement of the said guide member away from the commutator.

5. In an induction motor, a commutator having the outer end of its segments beveled to afford faces in a common conical surface, a shaft coaxial with and projecting beyond the commutator, a stop member mounted on the shaft at a fixed distance from the commutator, an inner metal cup having its mouth directed toward the commutator and slotted at its mouth end to afford fingers adapted to engage the said beveled segment faces, the said cup having the radially outward portion of its bottom sloping inwardly toward the commutator to afford a frustro-conical cam portion; an assemblage of flat weights engaging the outer face of the said cup bottom, each weight having an arcuate outer edge portion beveled to conform substantially to the said cam portion, the weights assemblage including means for spacing the weights symmetrically about the axis of the commutator while permitting movement of the weights radially of the commutator, an outer cup freely housing the said inner cup and having its bottom spacing the weights from the said top member, and a compression spring interposed between the commutator and the bottom of the inner cup.

6. The combination with a motor having a shaft projecting beyond the end of its commutator, of a bushing detachably secured to the shaft and having an enlarged head spaced from the commutator; two guides independently journaled on the shank of the bushing, the outer guide engaging the inward face of the bushing head; an interconnected and radially expandible weight assembly interposed between the two guides and including weights having radially outer cam faces, the inner guide having an annular cam portion engaged by the said cam faces when the motor is halted, the weights having radially inner faces engaging the shank of the bushing when the motor is halted; and a compression spring continually urging the inner guide outwardly; the inner guide having an annular portion disposed for engaging the commutator when the inner guide is moved against the resistance of the spring.

Signed at Chicago, Illinois, July 22nd, 1927.
